SELF INKING STAMP

Filed Nov. 22, 1926

FIG. I

FIG. II

KARL KLEIN
Inventor

By: *Ben V. Zillman*
Attorney

UNITED STATES PATENT OFFICE.

KARL KLEIN, OF ST. LOUIS, MISSOURI.

SELF-INKING STAMP.

Application filed November 22, 1926. Serial No. 149,830.

My invention relates to improvements in stamping mechanisms, and more particularly to stamping mechanisms somewhat similar to the ordinary rubber stamps, and has 5 for its principal objects the production of a stamping mechanism which shall be self-inking, simple, convenient, light and compact, extremely economical, reliable, and efficient and satisfactory for use wherever found 10 applicable.

The present type of self-inking stamp is a relatively complicated mechanism, having numerous parts cooperating with each other, some of the parts being stationary, and others being movable relatively to one another, these stamps being rather expensive due to their complex construction.

One of the objects of my invention is to make a stamp, that although self-inking, 20 yet will comprise only relatively fixed cooperating elements, and will depend upon the material of the parts themselves to accomplish self-inking, utilizing the physical properties of the various elements.

25 Many other objects and advantages of the construction herein shown and described will be obvious to those skilled in the art to which this invention appertains, from the disclosures herein given.

30 To this end, my invention consists in the novel construction, arrangement, and combination of parts herein shown and described, and more particularly pointed out in the claims.

35 In the drawings, wherein like reference characters indicate like or corresponding parts throughout the views,

Figure I is a longitudinal cross-section taken through the improved stamp;

40 Figure II is a bottom face view of the same; and

Figure III is a cross-section taken substantially on the line 3—3 of Figure I.

In the drawings, wherein I have illustrated 45 the preferred embodiment of my invention, which in the present instance is shown as a hand type of stamping device having a handle 1 whereby the stamp may be grasped for use and by means of which the stamp may 50 be hung up when out of use.

The frame or body of the stamp is indicated at 2, and generally speaking, the same comprises a block having a chamber or opening 3 upwardly from its bottom, and 55 to said block the handle 1 is fastened in any

suitable manner. This chamber is preferably formed with inclined side walls 4 and one end may be removably closed by a metal plate 5, for a purpose to be hereinafter described.

Within the opening 3 of the block a source of ink supply is provided, which in the present instance comprises a pad 6, of felt or other suitable material that will absorb the relatively heavy ink used for the purpose 60 and retain it for long periods of time.

The characters of the design that it is desired to reproduce or imprint upon suitable surfaces, such as upon bills, letters, etc., are indicated at 7—7', said imprinting elements 70 being preferably made of some material that will absorb and permit the stamping ink to impregnate its fibers, so that when the rear of the elements are in contact with a source of ink supply as shown at 7', that portion 75 being shown as the rear of the elements, said ink will be drawn through the same to the front or printing face of the elements, and in this manner provide an automatic inking feed for the elements.

In order that only the desired portions of the printing elements will reproduce their outlines upon the surface upon which the stamp is pressed, a backing sheet 8 is used and is preferably made of relatively thick 85 material as shown, this sheet preferably being substantially impervious and mounted in proximity to the absorbent pad 6 and covering one face of the same.

The pad and sheet are arranged within the 90 dove-tailed opening 3, compressing the same to wedge them in place firmly, and whenever it is desired to remove or replace the pad or sheet for re-inking of the pad or for renewal or any other purpose, the fastening screw 9, 95 holding the end of the opening 3 closed, is first removed, after which the desired movement may be made. After replacing the parts, the plate 5 is again fastened in position and the parts will remain thus.

From the foregoing description it is seen that I have provided a self-inking stamp, in which the material of the imprinting characters is such that they will, of themselves, 100 conduct the printing ink from the source of supply, in this instance the pad, onto their faces, so that when the stamp is pressed onto the surface desired the characters will be imprinted upon the latter. Pressure will cause the rear portions of the elements 7' to contact 105 110

more closely with the pad and thus take up more ink and carry it to the face of the elements.

I have found that fibrous materials such as string, felt and similar products serve satisfactorily as imprinting elements.

Having thus described my invention, it is obvious that various immaterial modifications may be made in the same without departing from the spirit of my invention; hence I do not wish myself to be understood as limiting myself to the exact construction, form, arrangement, and combination of parts herein shown and described, or uses mentioned, except as limited by the claims.

What I claim as new and desire to secure by Letters Patent is:

1. A self-inking stamp, comprising an ink-saturated pad, a non-metallic, substantially impervious backing sheet over one face thereof, and a pervious design on said sheet, the rear of said design communicating with said

pad; whereby the inking fluid will be automatically fed only through the pervious design when the stamp is pressed against a surface to be inked. 25

2. A stamp, comprising an ink-absorbent pad, a plurality of imprinting characters adapted to conduct ink from said pad through the rear of the characters to their face, and a fixed backing member of resiliently compressible material for carrying said characters. 30

3. A self-inking stamp, comprising a source of ink supply, a non-metallic backing sheet covering one face thereof, imprintable characters upon said sheet and projecting beyond the face of the latter and communicating at their rear with said source of ink supply, whereby the printing faces of said characters will be automatically self-inked whenever the stamp is pressed against a surface to be imprinted. 35 40
